R. W. ZIERLEIN.

GAS LAMP.

APPLICATION FILED FEB. 5, 1908.

900,817.

Patented Oct. 13, 1908.

UNITED STATES PATENT OFFICE.

RICHARD W. ZIERLEIN, OF ST. LOUIS, MISSOURI, ASSIGNOR TO PARIS LAMP MANUFACTURING COMPANY, OF ST. LOUIS, MISSOURI, A CORPORATION OF MISSOURI.

GAS-LAMP.

No. 900,817.

Specification of Letters Patent.

Patented Oct. 13, 1908.

Application filed February 5, 1908. Serial No. 414,371.

To all whom it may concern:

Be it known that I, RICHARD W. ZIERLEIN, citizen of the United States, residing at St. Louis, State of Missouri, have invented certain new and useful Improvements in Gas-Lamps, of which the following is a full, clear, and exact description, reference being had to the accompanying drawings, forming a part hereof.

10 My invention has relation to improvements in gas-lamps (or vapor-burning lamps), particularly those identified in the trade as gas arc-lamps, and it consists in the novel details of construction more fully set forth in the specification and pointed out in the claims.

In the drawings, Figure 1 is an elevation of a gas arc-lamp having my invention applied thereto; Fig. 2 is an enlarged vertical section 20 of the bottom draft-shield and support therefor, and the strainer disk, taken on the line 2—2 of Fig. 3; Fig. 3 is a horizontal section on the line 3—3 of Fig. 2; Fig. 4 is a vertical sectional detail of the gas regulating valve; Fig. 5 is a detached elevational view of the 25 upper end of the pilot burner; Fig. 6 is a perspective of the key by which the gas regulating valve is manipulated; and Fig. 7 is a perspective detail showing one of the pock-30 ets or depressions on the flange of the draft-shield, and the bracket arm engaging the same.

The object of my invention is to equip a gas-lamp of the character referred to with a bottom draft-shield and a coöperating strainer, which together with the globe supported by the shield, and with the upper hood will effectively protect the incandescent mantles of the lamp.

40 A further object is to provide a pilot burner which will supply a flame to each mantle-burner, the tips of the pilot-burner being renewable at any time.

A further object is to locate the gas regulating valve at a point where it can be readily manipulated from the floor where the lamp is suspended any considerable distance above the floor.

45 A further object is to provide a supporting spider for the draft-shield which at the same time will serve as a means for guiding the shield into position as the same, and the globe resting upon it are being placed into proper position on the lamp.

50 The invention consists in other features

whose advantages will be better apparent from a detailed description of the invention which is as follows:—

Referring to the drawings, 1 represents the top or hood of the lamp, 2, the shade, and 3 the globe as usual. The lower end of the gas-supply pipe 4 is coupled to the upper chambered section *a* of a hollow casting comprising in addition the hollow burner-arms *b*, *b*, and a depending tubular boss *c*, the portion *a* 60 communicating with the passages of the arms *b*, *b*, through a port 5 which is controlled by the conical seat of a screw-valve 6 mounted in the boss *c* and terminating at the lower end in a square or polygonal head 7. 70 A suitable packing ring *d* and gland *e* are secured to the boss *c* to form a gas-tight joint. The valve may be turned to proper position at any time, when the lamp is hung above the floor, by the stick or key *S* provided with 75 a suitable socket *s* to engage the head 7 of the valve (Fig. 1). Leading from the chambered section *a* of the bottom casting is a hollow boss *b'* to which is coupled a branch pipe 4' whose upper end terminates in a hollow head 4'' to which the pilot burner-tips 8, 8, are screwed. Each tip supplies a flame to the burner tubes 9, 9, over which the mantles *M* are suspended, the tubes 9, 9, being open at the bottom to the atmosphere, 80 and receiving their proper complement of gas through the burner-tips 10, 10, carried by the ends of the arms *b*, *b*. The manner of supporting the tubes 9, 9, is not material as my invention is not concerned with said detail. 90 One conventional manner is illustrated in the drawings, and requires no detailed description.

Passed over the gas-pipe 4, and secured thereto in any mechanical manner directly above the chambered section *a* of the bottom valve-casting, is the central hub of a spider composed in the present instance of such central hub and a series (preferably three) of arms 11, terminating at their free ends in 95 depending beveled fingers 12. These fingers serve to guide into position the upper globe-supporting flange 13 of the draft-shield 14 as the latter with its globe are raised into position on the supporting arms of the spider. 100 The edge of the flange 13 has cut therefrom a series of notches *n* through which the arms 11 are free to pass, after which by giving the shield a turn of sixty degrees, the ends of the arms will automatically enter the depressions 110 110

or pockets *p* formed in the shield-flange at points intermediate the three notches *n* referred to. The form of the shield 14 is on the order of an inverted cone, and by the 5 time the shield is raised into position on the spider arms, the bottom and smaller opening of the shield is only slightly removed from the strainer or perforated filter disk or plate 15, the latter being first passed over the 10 screw valve 6 before the valve is screwed into the boss *c* of the valve-casting; and while the filter or strainer eliminates all dust and solid particles from the air fed to the burners, it at the same time permits the filtered air to pass 15 freely through it.

It may be stated that by the time the shield with its globe is properly adjusted and supported on the spider arms 11, the upper end of the globe comes up against the basal 20 flange of the hood, and since the hood is itself surmounted by the upper draft shield 1', it follows that all the delicate parts such as the mantles are protected from injury and from draft, all dirt is kept from the burners, and 25 hence there results a lamp of the highest possible efficiency, the quantity of gas being easily regulated by a careful adjustment of the valve 6 in the manner indicated.

Having described my invention what I 30 claim is:—

1. In combination with the supply-pipe of a gas-lamp, a burner at the lower end of the pipe, a terminal valve for regulating the flow of the gas to the burner, a filter or strainer 35 disposed below the valve-casing, a draft-shield open at both ends passed about the burner, means for supporting the draft-shield, the filter being adapted to substantially close the bottom opening of the shield 40 when the latter is in position on the lamp, and means on the shield for supporting a suitable globe, substantially as set forth.

2. In combination with the supply-pipe of a gas-lamp, burners disposed at the lower end 45 of the pipe and deriving their supply therefrom, a spider having radiating arms disposed about the bases of the burners, a draft-shield adapted to be passed around the burners and having cut-away portions or 50 notches to permit the free passage therethrough of the ends of the arms aforesaid,

pockets disposed between the notches for locking the shield, the shield being adapted to be supported by the arms when turned sufficiently to bring the notches out of alignment with said arms, substantially as set forth. 55

3. In combination with the supply-pipe of a gas-lamp, a series of burners at the lower end of the pipe, a terminal rotatable valve 60 for regulating the flow of the gas to the burners, a filter or strainer disposed about the axis of the valve, a draft-shield open at both ends passed about the burners, means for supporting the draft-shield, the filter being adapted to substantially close the bottom opening of the shield when the latter is in position on the lamp, and means on the shield for supporting a suitable globe, substantially as set forth. 70

4. In combination with the supply-pipe of a gas-lamp, a hollow burner casting at the lower end of the pipe, incandescent mantle burners leading from the casting, a gas-regulating screw-valve mounted in line with the 75 axis of the supply pipe and having a section projecting beyond the casting, a perforated screen or filter-disk disposed about the valve, a spider having a series of radiating arms secured to the pipe above the casting, the arms 80 terminating in depending beveled guide-fingers, a draft-shield having an upper notched globe-supporting flange adapted to be passed above the spider arms and by proper rotation be supported on the arms, said flange 85 being provided with a series of pockets for the reception of the arms whereby the shield becomes locked against accidental displacement, the filter serving to substantially close the lower open end of the shield when the 90 latter rests on the spider, and a hood with which the globe mounted on the shield cooperates to practically inclose the burners and mantles from outside interference, substantially as set forth. 95

In testimony whereof I affix my signature, in presence of two witnesses.

RICHARD W. ZIERLEIN.
